Attorney, Agent, or Firm—Sanford Astor

[57] **CLAIM**

The ornamental design for a conduit for managing wires, as shown and described.

DESCRIPTION

FIG. 1 is a cross-sectional perspective view of the conduit for managing wires of my new design showing the environment in broken line;

FIG. 2 is a top plan view thereof;

FIG. 3 is a front elevational view thereof;

FIG. 4 is a bottom plan view thereof, both sides being the same;

FIG. 5 is a rear elevational view thereof;

FIG. 6 is a cross-sectional view thereof shown on an enlarged scale, taken along line 7—7 of FIG. 5; and,

FIG. 7 is a cross-sectional view thereof shown on an enlarged scale taken on lines 7—7 of FIG. 5 showing the device in the open condition.

The irregular ends in FIGS. 1—5 are intended to indicate an article of undeterminate length.

The broken line showing throughout the views is included for the purpose of illustrating environmental structure only and forms no part of the claimed design.
